Des. 225,325
Patented Dec. 5, 1972

225,325

COMBINED BRINE TANK AND WATER SOFTENER UNIT

William J. Marsh, Garden Grove, Calif., assignor to
Robert Marsh Enterprises, Inc., Santa Ana, Calif.

Filed May 5, 1971, Ser. No. 140,638

Term of patent 14 years

Int. Cl. D23—01

U.S. Cl. D23—3

FIG. 1

FIG. 2.

FIG. 3.

FIG. 4.

FIG. 5.

FIG. 1 is an exploded perspective view of a combined brine tank and water softener unit showing my new design;

FIG. 2 is a top plan view thereof;

FIG. 3 is a side elevational view thereof;

FIG. 4 is a front elevational view thereof; and

FIG. 5 is a rear elevational view thereof.

I claim:

The ornamental design for a combined brine tank and water softener unit, as shown.
